CLAIM

The ornamental design for an elastic holder as shown and described.

DESCRIPTION

FIG. 1 is a top, isometric view of a first embodiment of an elastic holder for holding 8 pieces of invisible elastic;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a top, isometric view of a second embodiment of an elastic holder for holding 10 pieces of invisible elastic;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines depict portions of the elastic holder which form no part of the claimed design.

1 Claim, 8 Drawing Sheets
